UNITED STATES PATENT OFFICE.

HOMER P. CHANDLER, OF MANSFIELD, OHIO, ASSIGNOR TO THE OHIO BRASS COMPANY, OF MANSFIELD, OHIO, A CORPORATION OF NEW JERSEY.

SECTIONALIZING SWITCH.

Application filed April 28, 1925. Serial No. 26,506.

My invention relates to a circuit controlling device and particularly that class of device known as a sectionalizing switch for use with trolley conductors.

5 It is particularly adapted for use in mines for cutting the trolley into sections either by hand or automatically. In the present invention I have incorporated in the usual standard hand operated sectionalizing switch means whereby the switch will be automatically opened through the instrumentality of the current collector as it passes the sectionalizing device and also 10 means for automatically opening the sectionalizing device if the current flowing therethrough should exceed a predetermined amount.

There are a great many different applications to which my device may be placed in 20 connection with trolley circuits, but the simplest use is in a main haulage way of mines. In such use the trolley wire is cut up into a plurality of sections between the main opening and the interior end of the 25 haulage way and a sectionalizing switch is positioned between the adjacent ends of the trolley wire whereby the various sections may be rendered dead or alive depending upon whether the trolley is in use for haulage purposes or not.

The device is closed by hand and opened 30 automatically by the current collector or by an excess of current. Assuming that a locomotive starts at the mine entry to run to the rear of the mine, the operator will close 35 the first sectionalizing switch thereby energizing the first section of trolley which will permit the locomotive to run to the second sectionalizing switch and this when closed 40 by the operator will energize the second section of trolley wire. This operation is continued until the locomotive has reached its destination. Upon the return trip, means is provided for tripping the sectionalizing 45 device as the current collector passes beneath and in engagement with the sectionalizing device and opening the same so that the section of trolley wire back of the locomotive, and controlled by the last sectionalizing switch passed by the locomotive, will be dead. These devices will be successively 50 automatically opened by the current collector as the locomotive moves to the entry of the mine.

Should the locomotive use an excessive amount of current or some accident take 55 place, such as the short circuiting of the trolley, one or more of the sectionalizing switches between the source of trouble and the source of power will automatically open 60 thus preventing trouble at some other point of the system nearer the source of power.

My invention resides in the new and novel construction, combination and relation of the various parts hereinafter fully described and 65 shown in the accompanying drawings.

In the drawings:

Fig. 1 is a top view of my invention showing the device in a closed position, that is, with the end castings electrically and mechanically connected.

Fig. 2 is a side view of Fig. 1 looking at the device from the handle operating side.

Fig. 3 is a side view in elevation of my invention taken from the opposite side of 75 Fig. 2.

Fig. 4 is a bottom view of my invention in which the end members are electrically and mechanically connected as is the case when the switch is in condition to allow the 80 passage of a current collector there-across.

Fig. 5 is a bottom view of my invention similar to that shown in Fig. 4, but with the switch open, that is, the end members are not electrically connected nor mechanically 85 connected.

Fig. 6 is a sectional view on the line 6—6 of Fig. 4.

Fig. 7 is a view of the latch employed to engage with the switch member of my invention to hold it in a closed position as 90 shown in Fig. 3.

Fig. 8 is a schematic arrangement to show the manner in which the circuits are made up.

In the preferred embodiment of my invention I employ an insulating member 1 which is usually made of wood and which material is inexpensive, easily fabricated, strong and highly efficient for the purpose required.

To the ends of the member 1 are secured 100 terminal members 2 and 2' which are provided with a portion 3 which acts as a guide for the current collector and a projecting member 4 grooved to receive the end of a 105 trolley conductor 5. The groove 6 which receives the trolley conductor terminates in an enlarged opening 7 adapted to receive a

tapered cap on the end of the conductor 5 which will prevent the withdrawal of the trolley 5 when once in position. The terminal members 2 and 2' are provided with a 5 socket member 8 adapted to receive the end of the member 1 and secured to the end of the member 1 by the transversely disposed bolt 9 and the vertically disposed bolt 10. Projecting from the member 8 is a support 10 ing member 11 provided with a slot 12 there- in to receive a holding bolt by means of which the device may be secured to the roof of a mine.

The inner ends of the guide members 3 15 are spaced apart and the members 2 and 2' are insulated from each other when the switch is in an open position. In order to electrically connect the members 2 and 2' and to provide a runway therebetween for the current collector, I provide a vertically disposed bolt having a shank 13 and an enlarged head 14. I prefer to make the parts 13 and 14 of soft iron as I employ these parts as the core of an electromagnet. The lower end 25 of the shank 13 projects below the member 1 and on the lower end is mounted a guide member 15 and secured thereto by the trans- 30 verse pin 16. Between the member 15 and the member 1 and surrounding the member 16 is a flange 17 provided with a boss 18 to which is secured the insulated handle 19. The flange forms an integral part of the member 15 and is secured thereto so that when the handle 19 is rotated the member 35 15 will be rotated and also the members 13 and 14. Interposed between the mem- 40 bers 1 and 14 is a soft iron plate 20 which is later explained and a flanged washer 21. The guide member 15 is shaped to conform 45 with the inner ends 3 of the members 2 and 2' and when in a closed position forms a continuous runway between the inner ends of the members 2 and 2' for the current collector.

Projecting from the upper edge of the member 15 and at the ends are plates 22 and 23. These plates are preferably formed 50 integral with the member 15 which in turn is of soft iron. Also projecting from one end of the member 15 and adjacent the upper edge is a contact member 24 secured to the member 15 by means of the screws 55 25. The member 24, I prefer to make of spring copper or phosphorous bronze, and secured to the outer end is a contact mem- 60 ber 26 adapted to engage with the projecting contact member 27 on the member 2 when the switch is closed. Since the member 24 is in electrical contact with the member 15, it is quite apparent that when the handle 65 19 is thrown to its closed position, that the member 2 will be electrically connected with the member 15.

At the opposite end of the member 15 is 85 secured a spring contact member 28 which

is secured to the member 15 by means of the screws 29. In this case, however, the mem- 70 ber 28 is insulated from the member 15 by means of the insulating bushings and washers 30 interposed between the member 28, the screws 29 and the member 15. Secured to the outer end of the spring contact member 28 is a contact member 31 adapted to engage with the contact member 32 on the member 2'. If now the operat- 75 ing handle 19 is thrown to its closed position, the member 28 will be in electrical connection with the member 32, but the member 2' will not be in electrical connection with the member 15 for the reason that the mem- 80 ber 28 is insulated from the member 15.

Mounted in a recess in the upper edge of the insulating member 1 and surrounding the member 13 as a core is an insulated coil 33 shown as composed of a plurality of 85 layers of flat ribbon insulated from each other and having the outer end 34 connected to the member 28 and insulated from the member 15 by the same insulating means 30 as insulates the member 28 from the member 15. The inner end of the coil 33 is secured to a bushing 35, preferably by soldering, and this bushing is a tight fit on the core 13.

Referring to Fig. 8, it will be apparent 95 that if the switch handle 19 is thrown to its closed position that there will be an electric circuit from trolley wire 5 to trolley wire 5 through the members 2, 27, 26, 24, 100 15, coil 33, exterior lead 34, 28, 31, 32, 2' 105 and 5. It will also be apparent that if cur- rent is taken from the trolley 5 from the side of the device away from the source of power that the current will necessarily flow through the coil 33 and energize the 110 core 13, the amount of energization depend- 115 ing upon the amount of current flowing through the coil 33. In order to hold the switch in an open position and to tend at all times to open the switch when it is closed, 110 I attach a spring 36 to the switch member and to the lugs 37 shown as secured to the insulating member 1.

The member 20, preferably formed up of 115 heavy gauge soft iron, is mounted in close engagement with the member 13 and as the overhanging ears 38 which are positioned adjacent the contact members on the side of the device and the ears 38, together with the lugs 22 and 23, form the poles of the 120 core 13 and tend to act as a magnetic blow- out and extinguish the arc when the switch moves to an open position with current flowing through the device.

Mounted on top of the member 1 is a clevis standard 39 to which is pivoted by means of the pin 40 a latch 41 which is bent down- 125 ward and has at the end a detent 42. Mounted on the side of the member 15 is the clevis lug 43 which has a roller 44 mounted 130

therein and adapted to engage with the detent 42. The latch 41 projects downwardly and outwardly from the side of the device and is provided with a detent 42 adapted to engage with the roller 44 on the bracket 43. The end of the latch 41 is pointed and when the handle 19 is moved to its closed position the roller 44 will engage with the upper surface of the pointed end of the latch and move the latch downwardly until the detent and roller coincide when the latch 41 will be moved upwardly through the action of the spring 45 thereby holding the switch in its closed position. The switch 10 is now in condition for conducting current from one trolley section to the adjacent section through the device and also for conducting a current collector from one section to another across the device. Mounted on 20 the upper face of the member 1 is a bracket 46 and pivotally secured to the bracket 46 is a lever 47 which is so bent that one portion 48 is positioned above the latch 41 and another portion 49 projects downwardly along the side of the device and adjacent the guide 3 such that when a trolley 25 collector is moving across the device in the direction of the arrow it will engage with the portion 49 of the lever 47 and move the same in the direction in which the collector is moving, and this in turn will cause the portion 48 to pivot downwardly and into engagement with the latch 41 thereby moving the lower end of the latch 41 and the 30 detent 42 downwardly and disengaging the latch from the bracket 43 thereby permitting the switch to open under the influence of the spring 36.

In order to cause the switch to open under an excess flow of current I mount upon the upper face of the member 1 a bracket 50. Into this bracket is pivotally mounted an armature 51 by means of the pin 52. The armature 51 is positioned above the core 45 13-14 and when the current flowing through the coil 33 is in excess of a predetermined amount it will attract the armature 51 and the portion 53 which is positioned above the latch 41 will be brought into engagement with the latch 41 causing the same to move out of cooperative relation with the bracket 43 on the switch thereby releasing the switch in such a manner that the spring 36 will cause the switch to open. In order to adjust the amount of current which may flow through the coil 33 without automatically operating the switch I interpose between the end 54 of the armature 51 and the member 1 a spring 55 secured to the member 54 by means of an adjusting screw 56 and by means of this spring and adjusting screw the amount of current required to cause the armature to be tripped may be varied.

As I have described the operation of the

device as I proceeded with the description of the same, I will not repeat the operation again in full, but it will be apparent that the device may be opened automatically by and through the movement of the current 70 collector in one direction and also through an excess of current flowing through the operating coil and it is also apparent that the switch may be closed manually through the medium of the handle 19 and opened 75 manually by manipulating the member 47 or 51 or 41 which may be done by an operator moving these parts by means of an insulated tool or by means of a stick of wood.

I have combined in one device a sectionalizing switch, an insulator and an automatic circuit breaker, which to the best of my knowledge has never been done in the past and there will be many modifications to the construction which I have herein described, which may be made and which will occur to those skilled in the art, but which will embody my invention and, therefore, I do not wish to be limited other 90 than by my claims.

I claim:

1. An article of manufacture comprising in combination, an insulating member, members attached to each end to secure the adjacent ends of a trolley conductor thereto, means positioned between the adjacent ends of said members to guide a current collector from member to member and arranged to move out of alinement with the said members, means to hold the guide means in alinement, means tending to move said guide means out of alinement and electrically operated means to influence the holding means to release the guide means when an excess 100 current is flowing in said trolley conductor.

2. An article of manufacture comprising in combination, an insulated member, members attached to each end to secure the adjacent ends of a trolley conductor thereto, means positioned between the adjacent end of the members to guide a current collector from member to member and arranged to move out of alinement with the members, means to hold the guide means in alinement, means tending to move the guide means out of alinement, electrically operated means to influence the holding means to release the guide means when an excess current is flowing in said trolley conductor and means operated by the movement of the current collector to also move said holding means to its release position when the collector moves across the guide member.

3. In an article of manufacture, the combination of an insulated member, members attached to each end to secure the adjacent ends of trolley conductors thereto, means positioned between the adjacent ends of the members and mounted on the insulating 130

member to rotate about a vertical axis to guide a current collector from member to member and arranged to move out of alignment with the members, means to hold the 5 guide means in alignment, means tending to move the guide means out of alignment and means operated by the movement of the current collector across the device to operate the holding means and move it to its release 10 position and permit the guide means to move out of alignment.

4. The combination of a pair of end members held in a spaced relation by an insulating member, means on the end members to 15 connect a conductor to each member, means to electrically connect the end members, means tending to open the connecting means, means holding the connecting member closed and electrically operated means to trip the 20 holding means when the current flowing exceeds a predetermined amount.

5. In a section insulator, an insulating member, end members held in fixed, spaced and insulated relation by the insulating 25 member and adapted to receive the ends of adjacent conductor sections, movably mounted means to electrically connect the end members and electrically operated means to automatically disconnect the end 30 members when an excess current flows from one section to the other through the device when closed.

6. In a section insulator, the combination of a pair of spaced and insulated end members to which the ends of adjacent conductor 35 sections are secured, means to connect the end members including the coil of an electro-magnet and means operated by the electro-magnet to open the connecting means 40 when the current flowing from one section to the other section is greater than a predetermined amount.

7. In a section insulator, the combination of a pair of end members held in a fixed 45 and spaced position, means to secure conductors to the end members, movable means to bridge the gap to guide a current collector from end to end and to electrically connect the end members, manually operated 50 means to move the movable member to its closed position, means to hold the movable means closed, means to move the movable means to its open position, means operated by the movement of the current collector to automatically release the movable 55 means and means operated by an excess current to automatically release the movable means.

8. A sectionalizing switch comprising in 60 combination, a pair of conductor supporting members held in spaced relation by an insulating member, movable means to close the gap between the supporting members, means to hold the movable means closed, means 65 to move the movable means to its open

position and automatic operating means to release the holding means, the automatic means provided with an operating coil having its ends connected, one to each supporting member. 70

9. A sectionalizing switch comprising a pair of end members mounted on an insulating member in spaced, fixed and insulated relation and having means to secure thereto the ends of conductors, a rotatable member 75 to close the gap between the end members, means on one member to engage means on the movable member to electrically connect the said members when the gap is closed, means on the movable member but insulated 80 therefrom to engage means on the other end member, an energizing coil connected to the rotatable member and the insulated means thereon such that the end members are electrically connected when the movable member 85 closes the gap, means urging the opening of the rotatable member, means to lock the rotatable member in closed position and means operated by the coil when over-energized to move said lock to its released position. 90

10. A sectionalizing switch comprising a pair of end members, an insulating member to which the end members are secured in spaced and insulated relation, a movable 95 member to fill the gap between the end members and to move into and out of alignment with the end members, means to electrically connect the movable members to one end member when aligned and an electro-magnet 100 having its coil connected to the movable member and the other end member when the members are aligned.

11. A sectionalizing switch comprising an insulating member, a pair of spaced end 105 members having means to secure conductors thereto, a movable member adapted to open and to close the gap between the end members and means to open the gap by operating the movable member when an excess 110 current is flowing in one or both of the conductors.

12. A sectionalizing switch comprising an insulating member, a pair of spaced end members having means to secure conductors thereto, a transversely disposed pin supported by the insulating member, a movable member supported by the pin, an energizing coil receiving current from the conductors mounted on the pin and means 120 controlled by the magnet coil to move the movable member out of alignment with the end members when an excess current is flowing through the coil.

13. A sectionalizing switch comprising an 125 insulating member and a pair of end members secured to the insulating member in spaced relation, means to secure conductors to the end members, a movable member to be moved into and out of alignment with 130

the end members and means to automatically move the movable member out of alinement when an excess current flows through said conductors.

- 5 14. The combination with a section insulator comprising an insulating member and spaced end members mounted thereon and means to secure conductors thereto, of means manually operated to electrically connect the end members at will and automatically operated to disconnect the end members under predetermined conditions.
- 10 15. A sectionalizing switch comprising an insulating member, a pair of spaced end members mounted on the insulating member, means to secure conductors to the end members, a movable member to electrically connect and disconnect the end members, means to disconnect the end members by operating the movable member when an excess of current is flowing in one or both of the conductors, parts formed of magnetic material positioned adjacent the make and break points between the end and movable members, a coil associated with the magnetic parts and receiving current from the conductors and energizing the magnetic parts to form a magnetic field acting to extinguish the arc when the movable member opens the gap between the end members with current flowing.
- 15 20 25 30 35 40 45 40 45

16. An article of manufacture comprising an insulating member, end members mounted on the insulating member in spaced relation and having means to secure conductors thereto, a movable member to open and close the gap between the end members, means to move the movable member to its open position, means to hold the movable member in its closed position, electrically operated means to act on said holding means to release the same when an excess of current is flowing through the conductors, means operated by the movement of a current collector to act upon the holding means to move it

to its release position, means to move the movable member to its closed position and means controlled by the electrically operated means to set up a magnetic field to extinguish any arc-formed between the end and movable members.

17. A sectional insulator comprising a pair of conductor holding members, spaced apart and mounted in an insulating member, a movable member to open and close the gap between the holding members, means to hold the movable member in closed position, means urging the opening of the movable member and pivotally mounted means to be engaged by a moving current collector to move the pivotal means into engagement with the holding means to release the same from the movable member when in the closed position.

18. A sectional insulator comprising a pair of spaced conductor holding members mounted on an insulating member, a movable member arranged to be manually moved into alinement with the holding members to guide a current collector across the gap between the holding members, means urging the opening of the movable member and means to hold the movable member in a closed position and to be released by an excess flowing to the current collector in moving across the device from one holding member to the other.

19. An article of manufacture comprising an insulating member, holding members attached thereto in spaced relation and having means to secure the ends of conductors thereto in insulated relation and a circuit breaker mounted on the insulating member and arranged to connect the conductors and electrically operated to automatically disconnect the conductors under predetermined conditions.

In testimony whereof I affix my signature.

HOMER P. CHANDLER.
